RAM JET ENGINE AND FLAME HOLDER
THEREFORElbert R. Sargent, Ferguson, Mo., assignor to
McDonnell Aircraft Corporation, St. Louis, Mo.,
a corporation of Maryland

Application April 5, 1948, Serial No. 19,141

7 Claims. (Cl. 60—35.6)

1

This invention relates to ram jet engines and is more particularly directed to an engine having a low ratio length to diameter and suitable for use in aircraft or parts thereof moving at sub-sonic speeds.

The object of this invention is to provide an improved ram jet engine that is capable of delivering large quantities of power, will occupy comparatively small space, and will be relatively low in weight.

In the drawings:

Fig. 1 shows a longitudinal sectional view of the improved ram jet engine.

Fig. 2 is an end view looking toward the left in Fig. 1.

Fig. 3 is an end view of the resonance suppressor.

Fig. 4 is a side elevational view of the resonance suppressor.

Fig. 5 is an end view of the flame holder support for the jet engine.

Fig. 6 is a side elevational view thereof.

Fig. 7 is an end view of an air inlet guide for the jet engine.

Fig. 8 is a side elevational view thereof.

Fig. 9 is an end view of the flame holder; and

Fig. 10 is a side elevational view thereof.

The improved ram jet engine consists of a body member 1 whose section along the minor axis is substantially circular and whose section along its major axis is substantially elliptical and is provided with an opening 2 through which air enters and the opposite end is of a substantially reduced section to form an exit area or nozzle 3. The ratio between the length and diameter is comparatively low so that over-all dimensions are kept at a minimum for optimum output. In order to protect the nozzle to prevent burning and distortion, in some instances, it may be desirable to provide a reinforcing ring 4 preferably made of some heat resisting material that circumscribes the entire body member 1. A bracket 5 is secured to the body member 1 at one side thereof to facilitate attachment to a body to be propelled, the instant engine being particularly suitable for use on the outboard ends of rotor blades for helicopters.

A dished support 6 of generally cylindrical shape is assembled in the tubular member 1 adjacent the inlet 2 in which a plurality of flame holders 7 are assembled. These flame holders are made up in the form of fan blades 8 and are stationarily secured in suitable apertures 9 cut into the support 6. The flame holders, sometimes called swirl vanes, are secured to the outlet discharge ends of fuel tubes 10 that are secured to a fixture 11 to which a conduit 12 is connected which leads to and is connected to a suitable source of fuel supply. The swirl vanes may be positioned so that all of them rotate air entering the combustion chamber in the same di-

2

rection or they may be installed so that every alternate one rotates air in the opposite direction. The fuel tubes 10, conduit 12 and fixture 11 are rigidly supported in the body member 1 by being connected to the flame holders 7 and the conduit 12 being rigidly secured in the wall of the body member 1. A centrally disposed flame holder 13 is projected forwardly so that it lies substantially just inside the inlet 2. A fitting 14 surrounds the circumferentially arranged flame holders 7 and extends to the periphery of the inlet 2, the fitting 14 being suitably arranged therein so as to provide a smooth uninterrupted surface for the flow of air. A fixture or fitting 15 surrounds the projected flame holder 13 and is then fitted interiorly of the circumferentially arranged flame holders 7 to form the second uninterrupted surface for passage of air. The fittings 14 and 15 may, if so desired, be shaped and formed so that at the position 16 indicated between the arrowheads, the passage is smaller in area than at the entrance thereof or at the entrance side of the flame holders 7 so as to have a diffusing or Venturi effect. However, the preferred construction is to so shape those surfaces as to not have the Venturi effect and to permit the free flow of air to the flame holders.

Another fixture 17 is assembled into the body 1 of the ram jet engine and surrounds the circumferentially arranged flame holders 7 and then is gradually flared outwardly so that it lies against the interior surface of the body member 1. The function of this member is to suppress the resonance effect produced in the body 1 of the ram jet engine which occurs during the combustion of rich fuel mixtures to thereby eliminate a large amount of undesirable noise and improve the range of operation of the engines. The resonance suppressor is suitably shaped so that it will closely fit each of the flame holders and enable the air to freely flow into the combustion chamber 18 of the ram jet engine. The resonance suppressor 17 is necessary for smooth burning of the ram jet engine. When the element is omitted, a step is formed between the swirls 7 and the body member 1. A step is frequently used to promote flame stability in burners of this type. However, tests with resonance suppressor 17 omitted produced rough burning accompanied with inferior thrust and range of operation. Smooth burning and efficient operation is obtained with a smooth transition from the outlet of the swirl 7 to the body member 1, thus preventing turbulence and back flow in the combustion chamber which causes rough burning in the burner. The fuel discharged from the tubes 10 is mixed with the air that passes through the flame holders 7, the blades thereof deflecting the air currents so as to produce a swirl or churning effect in the diffusion chamber 19 and thoroughly mixing air and fuel

at this point. Initial ignition of the fuel is accomplished by a spark plug 20 suitably installed in the body 1 of the ram jet engine and after initial ignition the burning is continuous as is customary in engines of this type.

The above described structure presents a compactly arranged ram jet engine that provides adequate means for retarding the air entering the ram jet engine, introducing fuel at this point so as to obtain a thorough mixing of the fuel so as to obtain a more complete combustion of fuel, and in turn obtain optimum power output. The structure 17 very materially reduces the noise of the engine and improves ranges of usable fuel air ratios and thereby produces a very desirable power unit for aircraft installations and by reason of its construction, the engine will commence operation at speeds materially lower than is customary for the conventional ram jet engine.

Reference was made above to the low ratio between overall length and diameter of the engine body. The swirl vane flame holders retard the movement of air but allow it to flow easily therethrough into the combustion chamber. By reason of the retarding action on the entering air, combustion of the fuel takes place in a much shorter distance than would be required if the swirl vane were not present. The combustion of fuel is, therefore, completed in a short distance, thus resulting in an engine body having a low ratio between its overall length and diameter.

What I claim is:

1. A jet engine comprising a tubular body substantially cylindrical in section in one dimension and substantially ellipsoidal in a transverse direction; a plurality of swirl vane flame holders assembled in one end of said body; means to introduce fuel into said tubular body immediately behind said swirl vanes; and a resonance suppressor in said body surrounding said swirl vanes and projecting into and abutting the inner wall thereof.

2. A jet engine comprising a tubular body substantially cylindrical in section through its minor dimension and substantially elliptical in section in its major dimension; means to introduce fuel into said body, a resonance suppressor mounted in the forward end of said body projecting thereinto and abutting the sides of the body; and swirl vane flame holders assembled in one end of said body with said suppressor to retard air movement into said body and hold a flame therein so that fuel combustion is substantially completed in said tubular body whose length is short in comparison to its diameter.

3. A jet engine comprising a tubular body substantially cylindrical in section along its minor axis and substantially elliptical in shape along its major axis; means in one end of said body to retard air movement and hold a flame including a plurality of swirl vanes circumferentially disposed in said body and a centrally disposed swirl vane projecting forwardly from the other of said swirl vanes; means assembled in the tubular body ahead of said swirl vanes to direct air into said swirls; means to introduce fuel into said body, means surrounding said forwardly projecting swirl vane to facilitate air flow into the plurality of swirl vanes; and a resonance suppressor assembled into said tubular body circumscribing said swirl vanes ex-

tending into the body and abutting the inner wall thereof.

4. A jet engine comprising a tubular body substantially cylindrical in section in one dimension and substantially ellipsoidal in a transverse direction; a plurality of swirl vanes assembled in one end of said body; means to introduce fuel into said tubular body immediately behind said swirl vanes and into the air stream passing therethrough; and a resonance suppressor in said body surrounding said swirl vanes and projecting into and abutting the inner wall of said body.

5. A jet engine comprising a tubular body substantially cylindrical in section through its minor dimension and substantially elliptical in section in its major dimension; means to introduce fuel into said body, a resonance suppressor assembled in said body; and swirl vane means assembled in one end of said body circumscribed by said suppressor to retard air movement into said body and hold a flame therein and causing combustion to occur within said tubular body whose length is short in comparison to its diameter.

6. A jet engine comprising a tubular body substantially cylindrical in section through its minor dimension and substantially elliptical in section in its major dimension; swirl vane means assembled in one end of said body to retard air movement into said body and to hold a flame therein; means to introduce fuel into said body, said swirl vanes causing combustion to occur within said tubular body whose length is short in comparison to its diameter; and means assembled in said tubular body to suppress resonance and circumscribing said swirl vanes and abutting the inner wall of the body.

7. A jet engine comprising a tubular body substantially cylindrical in section through one dimension and substantially elliptical in section transversely thereto; means to introduce fuel into said body; swirl vane means assembled in one end of said body to retard air movement into said body and to hold a flame therein and causing fuel combustion to occur within said tubular body whose length is short in comparison to its diameter; and a resonance suppressor assembled in said tubular body and circumscribing said swirl vanes and abutting the inner wall of the body.
